(57) **CLAIM**

The ornamental design for a vehicle side grille with fingernails, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front left elevated perspective view of a vehicle side grille with fingernails;

FIG. 2 is a front left perspective view thereof;

FIG. 3 is a rear right elevated perspective view thereof;

FIG. 4 is a rear right perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is another front view thereof, but with the vehicle side grille with fingernails mounted on a vehicle, the vehicle being unclaimed and shown in broken lines.
